UNITED STATES PATENT OFFICE.

THOMAS J. SAMMONS, OF CHICAGO, ILLINOIS, ASSIGNOR TO HIMSELF AND
EGBERT B. CLARK, OF SAME PLACE.

PROCESS OF POLISHING WOODEN RINGS.

SPECIFICATION forming part of Letters Patent No. 280,520, dated July 3, 1883.

Application filed January 10, 1881. Renewed December 4, 1882. (No model.)

To all whom it may concern:

Be it known that I, THOMAS J. SAMMONS, residing at Chicago, in the county of Cook and State of Illinois, and a citizen of the United States, have invented new and useful Improvements in Processes of Polishing Wooden Rings, of which the following is a full description.

In the drawings, Figure 1 shows a side view and a cross-section of a revolving receptacle or tumbler having holes in the ends for the passage of air. Fig. 2 represents a ring to be polished. Fig. 3 represents one of the balls used.

A specific description of the devices used will not be necessary, as the mechanism is not claimed.

Large numbers of wood rings are used for curtain-rings and other purposes, and such rings must be nicely polished, which heretofore has been accomplished with considerable labor. My invention is designed to save labor in polishing such rings, which I accomplish as follows: I first put the rings in a suitable revolving barrel or tumbler with a number of sanded balls small enough to pass freely through the

rings, and then cause the barrel or tumbler to rotate rapidly about two hours. The action of the balls on the rings is such that they will be in effect thoroughly sandpapered. I provide this tumbler or barrel with a number of holes in the circumference, to allow the sand and dust to escape.

I am aware that articles have been coated with japan and similar substances by revolving them in a vessel with small shot and rivet or collets, which serve to distribute the substance on the articles to be coated; but such is not my invention.

What I claim is—

As an improvement in polishing rings, the process herein described, consisting of tumbling the rings in a receptacle containing sanded balls of less diameter than the interior diameter of the rings for the purpose of imparting to the rings a smooth interior and exterior, as set forth.

THOMAS J. SAMMONS.
